UNITED STATES PATENT OFFICE

ELIE GRANAT, OF PARIS, FRANCE, ASSIGNOR OF ONE-HALF TO COMPAGNIE DES FORGES ET ACIERIES DE LA MARINE ET D'HOMECOURT, OF PARIS, FRANCE, A COMPANY OF FRANCE

AUTOMATIC SWITCH

Application filed February 8, 1927, Serial No. 166,800, and in France March 29, 1926.

My invention has for its object an improved switch adapted to break an electric circuit automatically when its voltage or intensity of the current flowing through it rises above a given value or else through a distant hand-control. My improved switch provides moreover for the automatic closing of the circuit as soon as the cause which has produced the breaking is suppressed, 10 an untimely closing being prevented as long as the said cause remains operative. My improved switch comprises a shaft bearing the movable contacts and normally held in the position corresponding to the closed circuit by a lever bearing against a cam keyed to the said shaft. This lever can be released by a finger secured to the armature of an electro-magnet which is excited and attracts its armature when the voltage or the intensity increases beyond a given value or in 15 any other suitable case. When the lever is thus released, a spring wound round the contact-bearing shaft brings the latter to the position corresponding to the opening of the 20 circuit.

The switch is cocked automatically by means of a constantly oscillating beam. Motion is imparted to this beam either constantly or at least whilst the circuit to be 25 controlled remains open by a servo-motor. To this beam is pivotally secured a catch normally held away from a cocking cam keyed to the switch-shaft. The catch engages this cam under the action of an independent pivoting finger whereby the beam 30 will rotate the cam through the said catch to turn the switch-shaft to its closed position in which it is locked. At the next oscillation of the beam the catch comes 35 against a tooth of the cam which pushes it back into its normal position, the pivoting finger being previously moved aside through the rotation of the cam. On the other hand 40 the cocking device cannot work too early whilst the electromagnet remains excited by the same cause, because the pivoting finger is locked outside the path of the catch by a part secured to the armature of the said 45 electromagnet, which part is moved aside 50

when the said armature is in its position corresponding to the closed circuit.

When a sudden closing of the circuit is desired in view of protecting the contacts against the effects of the arc which might flash in case of a slow closing, the device may be modified by way of example in the following manner. The cocking cam is disposed on a secondary shaft and serves to bind a spring which acts on a third cam secured to the switch-shaft and held in the position corresponding to the open circuit by a spring-urged lever. This lever is released only by a tooth of the cocking cam when this cam arrives in its cocking position. 55 Thus the spring previously tensioned by the rotation of the cam will suddenly, at this moment move the third cam and thereby bring the switch in its closed circuit position. 60

On appended drawings I have shown by way of example two forms of execution of my improved switch.

Figs. 1 and 2 are perspective views of a first form of execution respectively in positions corresponding to the closed and to the open circuit. Fig. 3 is a detail of the cock device. Figs. 4, 5 and 6 are explanatory diagrams of its working. Figs. 7 and 8 are perspective views of modified forms of the invention adapted to close the circuit suddenly shown respectively before and after cocking. Figs. 9, 10 and 11 are showing the positions of the parts during the cocking operation. 70

The construction shown in Figs. 1 and 2 comprises mainly a switch constituted by a shaft A borne in bearings not shown and to which are secured the movable contacts 7, 7'. These contacts close the circuit in the usual manner by connecting the parts 8 and 8' and the parts 8'' and 8''. The switch-shaft bears at one of its ends the cam 1 and is held in its closed position (Fig. 1) by the lever 4 pivoting round a stationary spindle 85 not shown and urged by the spring 3 anchored by suitable means not shown against the cam 1. This lever 4 bears against the tumbler 5 described hereinbelow and urged by the spring 6 against the lever. The 90

100

spring 2 secured at one end to the stationary part P and at the other to a point at the periphery of the cam 1 has a tendency to bring the shaft into the position corresponding to the open circuit (Fig. 2).

5 The tumbler 5 is secured to the armature of the releasing electromagnet E which is excited in case the intensity or voltage in the circuit to be protected increases beyond a given value. This electromagnet can also 10 be excited from a distant control part when it is desired to cut off the current.

It may be readily understood that the 15 spring 2 is bound as long as the tumbler 5 and the lever 4 are in the position corresponding to the closed circuit. This spring brings the switch in its open position (Fig. 2) by rotating the shaft A in the direction of the arrow f as soon as the armature of the 20 electromagnet E and the tumbler are rotated in the direction of the arrow f' and come into the position shown on Fig. 2 whereby the cam 1 is released. The current is thus 25 suddenly cut off as soon as the electromagnet is excited.

30 The cock device comprises a beam 15 pivotally secured on a shaft, parallel to shaft A, and not shown on the figures to which the cock motor M imparts an oscillating motion through the bevel pinions 20, 21, the worm 19, the worm wheel 18 mounted on a suitable spindle not shown and the crank 16. A catch 12 is pivotally secured as at 17' on the beam and has two possible positions one 35 of which I will term the lower position and the other the higher position. When in its lower position it engages a notch formed in cam 17 keyed to the end of the shaft A, whereas in the higher position it is moved 40 away from the said cam. A lever 13 subjected to the action of spring 14 is pivotally secured to the beam and engages either of the notches 12^a, or 12^b of the catch according as to whether the latter is in its higher or its 45 lower position. A three legged part 10 is pivotally engaged on a stationary axis shown diagrammatically at 10', and also has two positions. The leg 10 abuts against the rear of the catch 12 and serves to force the 50 said catch into its lower position at which time it is out of the path of the catch. The pivoting part is urged into its operative position by the spring 11, but is allowed to come into it only when the circuit is open 55 and the electromagnet E is no longer excited. When this is the case the tooth a of the cam rocking with shaft A releases the pivoting part 10 which was, for shaft A in its circuit closing position, forced in 60 its inoperative position by the said tooth a.

The pivoting part moves then into its operative position as soon as its lower leg is released by the elongated stop 9 controlled by the electromagnet E so as to keep the 65 pivoting part in its inoperative position as

long as the electromagnet is excited. When the electromagnet is not excited the stop 9 returns to its inoperative position whereby the pivoting part comes into its operative position.

70 The cocking operation may be easily understood by referring to diagrams shown on Figs. 4 to 6.

When the current is broken through the 75 rotation of shaft A the pivoting part 10 is held as stated in its inoperative position until the cause, which has actuated the shaft A has disappeared, that is, as long as the electromagnet E is excited. When the latter is no longer excited and the stop 9 is rotated, 80 part 10 comes in its operative position under the action of the spring 11. As the beam is constantly rocking and the top of part 10 is in the path of the catch 12, the latter will, by abutting against the former, be 85 caused to come into its operative position (Fig. 4) and, continuing to oscillate, with the beam whereupon it engages the notch shown between the teeth d and c on the cam. By reason of the shape of the notch as soon 90 as the beam and catch move towards the right, the catch will push the cam clockwise into the position shown on Fig. 5 wherein the main circuit is closed again and the pivoting part 10' forced back by the projection a on the cam into its inoperative position. When the beam returns to the 95 left, the catch 12 does not act on the cam. On the contrary the tooth d holds the catch elevated. The lever 13 is forced out of the 100 notch 12^b and enters notch 12^a whereupon the catch is caused to occupy, with reference to the beam, a position wherein it can 105 oscillate with the latter without contacting with the cam. As the pivoting part 10 is 110 inoperative it cannot act any more on the catch 12 which continues oscillating without 115 any action on the device.

120 The above described device provides perfect safety in operation. However it may 110 in certain cases be inconvenient as the closing of the circuit is not sudden and that the arcs ignited at the closure of the high tension circuits might hurt the contacts. It is 125 possible in the case of a high tension circuit 115 to modify the apparatus as shown on Figs. 7 and 8. In this modified form of execution, the cam 17 is mounted on an intermediary 130 shaft alined with shaft A and independent 120 of it, the catch and the pivoting part working 135 exactly as in the preceding case. The difference resides in that the cam 17 does not actuate the shaft A directly but binds the spring 22 which controls the cam 26 140 keyed to the switchshaft A. The ends 23 135 and 24 of a U-shaped lever are held by a 145 spring 25 against the two cams 17 and 26.

150 The working is similar to that of the above described apparatus. When the circuit is open (Figs. 7 and 9) the lever end 155

24 abuts against the end of the projection *c*' on the cam 26. When the catch 12 has rotated the cam 17 by a certain angle when the apparatus is to be cocked, the spring 22 is tensioned but the cam 26 is kept stationary by the lever end 24 until at the end of the movement the other lever end 23 comes against the projection *e* of the cam 17 (Fig. 10). The lever end 23 is thus raised together with the lever end 24 whereby the cam 26 is released; the cam 26 is thus urged by the spring 22 into its circuit breaking position (Fig. 11). It comes suddenly into this position and binds at the same time the spring 2 which is weaker than spring 22. The circuit is suddenly closed. When it is broken for any suitable cause, the cams 26 and 17 connected by the spring 22 are brought back together by the spring 2 into their circuit breaking position.

Evidently the above described devices are only disclosed by way of example. For instance the beam may be actuated only during the periods wherein the main circuit is opened this being provided by suitable auxiliary contacts. Thus the circuit of the cocking motor might be closed by two contacts borne by the cocking cam whereby the independently fed auxiliary motor works only when the said cam is in the position shown on Fig. 2.

The releasing electromagnet may be replaced by any other suitable mechanical or electric device. In a similar manner the auxiliary cocking motor might be replaced by a suitable electric or mechanical servo-motor. This servo-motor may be the shaft of the motor of the generator group feeding the circuit in which is inserted my improved protecting switch; the mechanical control of the cocking device may be provided through a magnetic clutch the circuit of which is closed only when the electromagnet E has released the switchshaft.

It should be noted that the apparatus can be controlled from a distance and be disposed at any suitable point. It can work with A. C. or D. C., with or without delay, the delay being obtainable by any suitable mechanical or electric means.

The apparatus can be provided with release and cocking levers for hand operation in case of damage to the said apparatus or of the lack of feed current for the auxiliary motor, these levers should be disposed so as to be reached only in case of absolute necessity; they can for instance be locked by means of a special key.

What I claim is:

1. In a switch of the class described, the combination with a shaft, of means whereby the shaft is brought into its circuit breaking position when the energy of the current in the circuit passes above normal value, means

79
in its circuit breaking position and operating to release said shaft to its circuit closing position, and means whereby the moving means are rendered inoperative during the time the energy of the current in the circuit remains above its normal value.

2. In a switch of the class described, the combination with a shaft, of an electromagnet adapted to be excited when the energy of the current in the circuit passes above normal value, means whereby the said electromagnet when excited serves to move the shaft into its circuit breaking position, a beam, means for causing said beam to oscillate constantly, a cam controlled by the shaft, a catch pivotally secured to the beam and adapted to assume two positions, in one of which it serves to act through the cam on the shaft in a direction to force the latter back into its circuit closing position, means for holding the cam in operative and inoperative positions, means for urging the catch to operative position, and means adapted to render the last mentioned means inoperative when the electromagnet is excited and when the shaft is in its circuit closing position.

3. In a switch of the class described, the combination with a shaft, of an electromagnet adapted to be excited when the energy of the current in the circuit passes above normal value, means whereby the said electromagnet, when excited, moves the shaft into its circuit breaking position, a beam, means for causing said beam to oscillate constantly, a cam controlled by the shaft, a catch pivotally secured to the beam adapted to assume two positions, in one of which it serves to act through the cam on the shaft in a direction to force the latter back into circuit closing position, means for holding the cam in operative and inoperative position, a pivotally mounted part movable into the path of movement of the catch to urge it into its operative position, a part controlled by the electromagnet and adapted to prevent the pivotally mounted part from moving into the path of the catch while the electromagnet is excited, means whereby the cam pushes the pivotally mounted part out of the path of movement of the catch when the shaft is in its circuit closing position, and means for urging the pivotally mounted part into the path of movement of the catch.

4. In a switch of the class described, the combination with a shaft, of an electromagnet adapted to be excited when the energy of the current in the circuit passes above normal value, means whereby said electromagnet, when excited, moves the shaft into its circuit closing position, a beam, means for causing said beam to oscillate constantly, a cam, elastic means adapted to transmit the rotation of the cam to the shaft, means

125

130

for rotating the shaft under the action of the elastic means only after a given angular rotation of the cam, a catch pivotally secured to the beam and adapted to assume two positions, in one of which it serves to act through the cam on the shaft in a direction to force the latter back into its circular closing position, means for holding the cam in operative and inoperative positions, means for urging the catch to its operative position, and means adapted to render the last mentioned means inoperative during a period when the electromagnet is excited and when the shaft is in its circuit closing position.

15 In testimony whereof I affix my signature.

ELIE GRANAT.
